Fig. 8. 12

This technical drawing shows a cross-section of a vaulted structure, likely a bridge or tunnel, with the following dimensions:

- Width of the vaulted opening: 97
- Width of the side walls: 92
- Width of the top walkway: 92
- Height of the vaulted arch: 96
- Height of the side walls: 96
- Height of the top walkway: 92
- Total height of the structure: 95
- Thickness of the side walls at the base: 12
- Thickness of the top walkway: 90

Material labels:

- GEO (Geological) - at the bottom left
- BY (Brick) - at the bottom center
- STM (Steel) - at the bottom right

UNITED STATES PATENT OFFICE.

GEORGE B. DAMON, OF BELVIDERE, NEW JERSEY, ASSIGNOR TO VULCAN IRON WORKS,
OF WILKES-BARRE, PENNSYLVANIA, A CORPORATION OF PENNSYLVANIA.

DRIER.

Application filed October 4, 1921. Serial No. 505,434.

To all whom it may concern:

Be it known that I, GEORGE B. DAMON, a citizen of the United States of America, residing at Belvidere, in the county of Warren and State of New Jersey, have invented certain new and useful Improvements in Driers, of which the following is a specification.

My invention relates to driers, and particularly to rotary driers of the double shell type shown in my copending application Serial No. 397,055, filed July 17, 1920, now Patent No. 1,447,929, dated March 26, 1923, of which the present application is in part a continuation. As pointed out in said application, the inner flue of the drier may be conical, with its small end arranged either toward the stack or toward the fire box. In the present application, so far as the invention relates to the shape of the flue, the latter is of the type in which the small end of the flue is arranged toward the stack, and is specific to this type as distinguished from the opposite arrangement shown in detail in the application above referred to.

I have also indicated various features of novelty in the present construction which have no dependence upon the particular shape of the flue or its arrangement, and as to these features so far as they present invention over the subject-matter of my copending application, the present constitutes a continuation thereof.

The features of improvement which I regard as my invention will be hereinafter pointed out in the specification and claims, or may be observed from the illustrative embodiment thereof in the accompanying drawings, in which—

40 Fig. 1 is a longitudinal side elevation of a drier installation in which my invention is embodied;

Fig. 2 is a plan thereof;

45 Fig. 3 is a broken side elevation drawn to an enlarged scale of the feed end of the drier;

Fig. 4 is an end elevation thereof;

50 Fig. 4^a is a vertical section through the fan shown in Figs. 3 and 4, the blades being in the position assumed when the fan is at rest.

Fig. 5 is a broken side elevation of the fire box end of the drier drawn to an enlarged scale;

Fig. 6 is a partial plan view of the feed 55 hopper and reciprocating feeder;

Fig. 7 is a longitudinal section therethrough showing the feeder at the end of its return stroke;

Fig. 7^a is a section on the line 7^a, Fig. 7; 60

Fig. 8 is a broken transverse section through the tempering chamber portion of the fire box end of the structure; and

Fig. 9 is a section through the drier cylinder. 65

The general installation is illustrated in Figs. 1 and 2, from which an arrangement similar to that indicated in my copending application above mentioned will be observed. Thus, the rotary cylinder 10 of the 70 drier extends between the fire box 11, or more specifically between the tempering chamber 12 thereof, on the one hand, and the stack 13 on the other hand. The shell carries the usual circumferential gear ring 75 14 which meshes with a pinion 15 driven through a suitable gear train from the pulley shaft 16, which is in turn driven by the belt 17 from the electric motor 18. Bearing rings 19 and 20 suitably spaced apart 80 upon the cylinder, run on suitable roller pairs 21 and 22 mounted on pedestals 23 and 24. The proper mesh of the gears 14 and 15 as well as a proper location of the delivery end of the cylinder with relation to the 85 fire box may be obtained by a suitable regulation of the bearing blocks 25 and 26 (Fig. 9) which are transversely adjustable on their bases 27 by means of adjusting screws 28 and 29. 90

Within the cylinder 10 and substantially concentric therewith is a conical flue 30 supported within the shell 10 by any suitable means, such as rigid struts 31 shown in Fig. 9, or by flexible links of the type indicated in my copending application. Projecting into the annular space 32 between the flue and shell, are flights 33 which serve to repeatedly cascade the material as it passes gradually through the annular drying chamber 32 from the stack end thereof to the fire box end thereof, as a result of the 100

general downward inclination of the cylinder from the stack and toward the fire box.

As will be noted, the space accorded between the flue 30 and the shell 10 at the stack end thereof, is sufficiently great, as a result of the conical shape of the flue, to permit the use of a mechanical feeder for introducing the wet material to the annular drying space 32. A suitable feeder is illustrated in Figs. 3 and 4, and on a larger scale in Figs. 6 and 7. As will be noted from Fig. 3, the stack 13 rises from a wind box 34, through a hole 35 in the side of which open the cylinder shell 10 and flue 30. Projecting through the opposite side of the wind box is a feed trough 36, to which material may be delivered through the hopper 37. Reciprocating in the trough 36 is a feeder comprising longitudinally extending shafts 38 having clamped thereon, at suitable adjustable intervals, a series of collars 39. Integral therewith are rigid stops 40 while pivoted thereon are push plates 41 which rest against the stops 40 on the feed stroke, but swing away from the same above the material in the trough on the return stroke, as illustrated in Fig. 7. A connecting rod 42 extends between the outer end of the shaft 38 and the crank 43 on the pulley shaft 44, which is driven by a belt 45, lay shaft pulley 46 and belt 47 from the electric motor 48. The shafts 38 carry cross spindles 49, with supporting rollers 50 upon which the feeder runs on the sides of the trough. Guides 51 mounted on opposite sides of the trough overlie the rollers 50 and restrain the feeder against displacement.

Above the wind box 34, and between the latter and the stack 13 is a fan chamber 52. The fan 53 arranged within this chamber forms the subject matter of a separate application filed by me October 4, 1921, Serial No. 505,435 and as therein set forth more fully, comprises unbalanced pivoted blades 53 which when the fan is at rest, assume a substantially perpendicular position and thus offer the least possible obstruction of the draft passage to the stack. It may be noted, however, that the fan is supported upon a vertical shaft 54 passing through the wind box 34 and having a step bearing 55 on the pedestal 56. On the fan shaft is a pulley 57 around which passes the belt 58 from the pulley 59 on the lay shaft 46. A lateral opening 60 affords access to the interior of the wind box 34, but is normally closed by a sliding door 61 in order to prevent leakage into the wind box.

In order to keep the fan blades clean and free from accumulation of dust or soot, which might prevent their proper functioning, I provide the fan chamber 52 with a lateral opening, which is normally closed by a door 52^a, through which access to the

interior of the fan chamber may be obtained by the attendant for brushing the blades clean.

Also mounted within the wind box is a damper plate 62 pivoted at 63 to the supporting lever arm 64. The latter is mounted in such position at 65 on the outer wall of the wind box that the damper 62 may be swung down to more or less close the discharge end of the flue 30 as may be necessary to maintain the desired draft through the flue. To operate the lever 64 I provide a link 66 connected to the lever at one end and projecting through the outer wall of the wind box at its other end, where it is provided with a handle 67 for convenient manipulation by an operator standing upon the adjacent platform 68. Serrations 69 on the lower face of the handle bar 66 engage the latch 70 on the bracket 71 to maintain the damper in adjusted position.

The material entering the annular drying chamber 32 is repeatedly cascaded therein by the flights 33 as the cylinder rotates. It eventually approaches the discharge end (Fig. 5) and falls in dried condition to the transversely arranged receiving trough 72.

A reciprocating scraper 73 of the same type as that used at the feed end of the drier may be employed to remove the dried material laterally to a pit 74. A bucket chain hoist 75 lifts the material from the pit and discharges it at any desired point. The scraper 73 and hoist 75 may be conveniently driven by an electric motor 76 through a belt shaft 77. Beveled gears 78 drive the crank shaft 79 for the scraper, while the chain 80 drives the sprocket for the chain hoist 75.

The fire box 11 is here indicated as accommodating a chain grate with a forced draft through the fire bed 82 from the tuyère box 83, to which the blast is admitted through conduits 84 (Fig. 2) from the fan 85. The products of combustion passing around the furnace arch 86 enter the tempering chamber 87, to which excess air, that is to say air in excess of that required to support combustion, is admitted through ports 88 controlled by valve shutters 89. The temperature of the gases may be lowered to a suitable extent by a greater or less opening of the shutters 89. The gases thus tempered pass through a checker-work 90 into a second tempering chamber 91, to which open further ports 92 controlled by similar shutter valves 93.

A third tempering chamber 94 is separated from the chamber 91 by the checker-work 95, and is similarly provided with shutter valves 96 controlling the admission of further excess air. The checker-work partitions 90 and 95 between the tempering chambers serve not only to effect a proper commin-

gling of the excess air with the products of combustion, but to stabilize the temperature of the gases passing through the drier regardless of variations in the intensity 5 of the fire. The flue 30 is extended beyond the shell 10 at the fire box end of the drier and opens into the tempering chamber 91. The gases passing into the flue are therefore at a higher temperature than those which 10 enter the annular drying chamber 32, which opens to the tempering chamber 94 most remote from the fire box. By properly adjusting the shutter valves, the temperature of the gases entering both the flue and the 15 annular drying chamber are so regulated with respect to the nature of the materials under treatment that the latter are not subjected to injurious heat.

In order to protect the checker-work 95 against possible mechanical injury during the rotation of the drier, I mount a collar 97 at the opening therein which receives the flue 30. A similar bearing collar 98 may be arranged in the end wall of the furnace in 20 which the shell 10 is received.

To drive blower fan 85, I preferably employ an electric motor 99 with a belt connection 100 to the fan shaft. The same motor may be employed to drive the chain 30 grate 81 through suitable transmission devices to the worm shaft 101.

Inasmuch as the fan 85 delivers a forced draft to the grate, the products of combustion in the fire box are slightly above atmospheric pressure, and the operation of the stack fan 53 may be necessary, under certain atmospheric conditions, to supplement the pull of the stack draft in order to draw through the flue and drying chamber, not 35 only the products of combustion but also the excess air admitted to the tempering chambers. The fan is preferably so operated as to effect a condition of balanced draft, that is to say, to insure a discharge through 40 the stack at a rate sufficient to carry off the products of combustion properly tempered by excess air, together with the moisture absorbed from the material by the gases as 45 they pass through the drier.

50 Where material is under treatment which is loath to part with its moisture, the arrangement of the conical flue, with its small end directed toward the stack, has the advantage of delaying the passage of the material 55 through the drier, since the flights on the flue instead of dropping the material further down the shell toward the discharge end thereof, drop it more nearly perpendicularly than is the case where the flue is cylindrical, like the shell, or has its smaller 60 end directed toward the discharge end of the drier, as in my copending application. While the latter construction accelerates the passage of material through the drier, and is for that reason desirable where the material

readily parts with its moisture, the present drier is of particular value when dealing with material such as coal, loam, clay, some iron ores, liminite, which give up their moisture slowly.

70 It may be further pointed out that the gases passing through the flue contract as they cool, and the construction accomodates this condition.

75 While the construction shown is suitable for carrying out the objects of my invention, it will be readily recognized that various modifications of construction and arrangement are possible which do not depart from the spirit and scope of what I claim as my 80 invention.

In résumé it may be pointed out briefly, in advance of the following claims, that the present construction presents improvements from the following standpoints: First, it 85 results in the slowing down of the travel of the material through the drier, which is desirable in view of the fact that the last few per cent of moisture in the material require the most time and heat for their extraction. 90 Second, the velocity of the gases through the annular drying chamber is retarded toward their discharge end, thus affording them a chance to deposit their entrained dust on the incoming wet material. Third, 95 ample space is afforded for the introduction of the wet material by some positive feeder device at the stack end of the drier. Fourth, proper regulation of the gases may be obtained by the tempering chamber. Fifth, 100 the wind box or expansion or settling chamber at the stack end of the drier affords a suitable arrangement for the elimination of the fines or dust carried out by the gases. Sixth, the fan makes possible a condition 105 of balanced draft through the apparatus, when using gases under pressure from the fire chamber. In other words, the stack fan provides a suction through the drier sufficient to take off the products of combustion 110 under slight pressure in the combustion chamber, together with the tempering air, while at the same time removing these gases at the lowest possible speed commensurate with desired draft conditions in order that 115 the dust particles may have opportunity to settle on the incoming wet material instead of being drawn off at high velocity through the stack. Seventh, the general arrangement of parts and specific construction of 120 integers are of a rugged, substantial character well adapted for the services which they are called upon to perform.

What I claim as my invention is—

1. A drier comprising a rotary shell and 125 inner flue, affording between them an annular drying chamber of gradually increasing cross sectional area from the gas intake to the gas outlet ends of the drier.

2. A drier comprising a rotary shell and 130

inner flue, affording between them an annular drying chamber of gradually increasing cross sectional area from the gas intake to the gas outlet ends of the drier, together with means for feeding material to the annular chamber at the gas outlet end thereof.

3. A drier comprising a rotary shell and inner flue, affording between them an annular drying chamber of gradually increasing cross sectional area from the gas intake to the gas outlet ends of the drier, together with means for feeding material to the annular chamber at the gas outlet end thereof, of, a receptacle to which dried material is discharged, and means therein for removing the material from said receptacle.

4. A drier comprising a rotary shell and inner flue, affording between them an annular drying chamber of gradually increasing cross sectional area from one end to the other, and having its bottom inclined in one direction, gas inlets and outlets at opposite ends of the drier, means for feeding material to the annular chamber at the gas outlet end thereof, a trough for receiving dried material discharged at the gas inlet end of said chamber, and a reciprocating member for removing said material from the receiving trough.

5. A drier comprising a rotary shell and inner flue, affording between them an annular drying chamber of gradually increasing cross sectional area from one end to the other, and having its bottom inclined in one direction, gas inlets and outlets at opposite ends of the drier, means for feeding material to the annular chamber at the gas discharge end thereof, means for receiving said material discharged at the gas inlet end of the chamber, and means for removing said material laterally from said trough, together with a conveyor to which the removed material is discharged.

6. A drier comprising a rotary shell and inner flue affording between them an annular drying chamber, a source of heating gases opening to the corresponding ends of said flue and annular drying chamber, in combination with a fan at the air discharge end of the drier for accelerating the passage of the gases through the latter.

7. A drier comprising a rotary shell and inner flue, affording between them an annular drying chamber, means for supplying gas under pressure to the corresponding ends of said flue and annular drying chamber, together with a fan at the air discharge end of the drier for accelerating the passage of the gases through the latter.

8. A drier comprising a rotary shell and inner flue, affording between them an annular drying chamber, and means for supplying at the corresponding ends thereof heated gases under pressure and at different

temperatures for said flue and drying chamber, together with a fan at the discharge end of the drier for accelerating the passage of the gases through the latter.

9. A drier comprising a rotary shell and inner flue, affording between them an annular drying chamber, means for supplying heated gases to said flue and annular drying chamber, a settling chamber at the opposite end of the drier to which the gases are discharged, and a fan for accelerating the passage of the gases through the settling chamber.

10. A drier comprising a rotary shell and inner flue, affording between them an annular drying chamber, a fire chamber for generating heated gases for the drier, checker-work through which said gases pass before entering the drier, an opening in said checker-work for the reception of the flue, and a wearing ring lining said opening to protect the same against mechanical injury during the operation of the drier.

11. A drier comprising a rotary shell and inner flue, affording between them an annular drying chamber, a fire chamber at one end of the drier, means for supplying forced draft to the fire chamber, means for leading the products of combustion under pressure through the intake ends of the flue and annular drying chamber at one end of the drier, and a fan at the other end of the drier for accelerating the flow of the heated gases through the drier.

12. A drier comprising a rotary shell and inner flue, affording between them an annular drying chamber, a fire chamber at one end of the drier, means for supplying forced draft to the fire chamber, means for leading the products of combustion under pressure through the intake ends of the flue and annular drying chamber at one end of the drier, a fan at the other end of the drier for accelerating the flow of the products of combustion through the flue and drying chamber, together with means for admitting excess air to the products of combustion between the fire box and the intake of the drier.

13. In a rotary drier, an outer shell and inner flue, affording between them an annular drying chamber, means for supplying heated gases under pressure and excess air to the flue and drying chamber at one end of the drier, in combination with a fan at the other end of the drier for inducing the flow of gases and excess air through the flue and drying chamber.

14. A drier comprising a rotary shell and inner flue, affording between them an annular drying chamber of gradually increasing cross sectional area from the discharge to the intake ends thereof, means for passing heated gases in the same direction through said flue and annular drying chamber from the discharge end of the latter, to

gether with a reciprocating feeder for introducing material to the drying chamber at the end of greater area.

15. A drier comprising a rotary shell and inner flue, affording between them an annular drying chamber, means for passing heated gases through the flue and annular drying chamber, a settling chamber to which said gases are discharged, a stack communicating with the settling chamber, and means for passing material through said settling chamber to the annular drying chamber.

16. A drier comprising a rotary shell and inner flue, affording between them an annular chamber, means for passing heated gases through the flue and annular drying chamber, a settling chamber to which said gases are discharged, a damper pivoted in said settling chamber, and means operable from the exterior thereof for closing to a greater or less extent the gas escape end of the flue.

17. A drier comprising a rotary shell and inner flue, affording between them an annular drying chamber, means for passing heated gases through the flue and annular drying chamber, a settling chamber to which said gases escape from the drier, a fan associated with the settling chamber for accelerating the removal of the discharged gases from said chamber, and means exterior to the latter for driving the fan.

18. A drier comprising a rotary shell and inner flue, affording between them an annular drying chamber, means for passing heated gases through the flue and annular drying chamber, a settling chamber to which said gases escape from the drier, a reciprocating feeder passing through the settling chamber for introducing material to the annular drying chamber, and a fan for accelerating the removal of the discharge gases from the settling chamber.

19. In a drier, a rotary shell and inner flue, affording between them an annular drying chamber, a settling chamber to which escape the gases passing through said flue and chamber, a feed trough passing through said settling chamber for leading

material to the annular drying chamber, in combination with a reciprocating feeder 50 working in said trough and comprising pivoted pallets having a one-way operative engagement with the material in the trough.

20. A rotary drier having at one end a settling chamber and a stack, a rotary stack 55 fan, a driving spindle therefor rising through the settling chamber, and means exterior to the latter for driving the spindle.

21. A rotary drier having at one end a 60 settling chamber and a stack, a rotary stack fan, a fan chamber interposed between the settling chamber and the stack, a spindle rising through the settling chamber to the fan chamber, and means exterior to said 65 chambers for driving the spindle.

22. A rotary drier having at one end a settling chamber and a stack, a fan chamber interposed between the settling chamber and the stack, a rotary stack fan arranged on a 70 vertical axis in said fan chamber, said fan chamber having a lateral opening to permit access to the fan arranged therein, a door normally closing said opening, a fan spindle rising through the settling chamber 75 to the fan chamber, and means exterior to said chamber for driving the spindle.

23. A rotary drier having at one end a settling chamber and a stack, a rotary stack fan arranged above the settling chamber, 80 and having blades mounted to automatically move to non-obstructing position when the fan is at rest, and means to drive the fan.

24. A rotary drier having at one end a settling chamber and a stack, a rotary stack 85 fan, a vertical fan spindle extending below the stack, a fan on said spindle, a top bearing for the spindle within the stack, a step bearing for the lower end of the spindle exterior to the stack, and means for driving 90 the exposed lower end of the spindle to rotate the fan.

In testimony whereof I have signed my name to this specification.

GEORGE B. DAMON.
